UNITED STATES PATENT OFFICE.

JAMES GREEN, OF BAY ST. LOUIS, MISSISSIPPI, ASSIGNOR OF ONE-THIRD TO ROBERT W. TAYLOR, OF BAY ST. LOUIS, MISSISSIPPI.

BOTTLE.

1,206,694.

Specification of Letters Patent. Patented Nov. 28, 1916.

Application filed March 1, 1916. Serial No. 81,494.

To all whom it may concern:

Be it known that I, JAMES GREEN, a citizen of the United States, residing at Bay St. Louis, in the county of Hancock and 5 State of Mississippi, have invented new and useful Improvements in Bottles, of which the following is a specification.

This invention relates to bottles and more particularly to the non-refillable type, and 10 has for an object to provide a bottle which, when the original contents have been withdrawn, can not be conveniently or commercially refilled.

A further object of the invention is the 15 provision of a bottle having few and simple parts which can be cheaply manufactured and easily assembled to provide a structure preventing the refilling of the bottle with an inferior or spurious fluid after the original 20 contents have been withdrawn. To this end use is made of a guard in the form of a tube or nipple and disposed to permit the contents of the bottle to be poured therefrom when the bottle is tilted, but which will 25 actuate to prevent refilling of the bottle, suitable means being also provided to prevent tampering with the guard for the purpose of securing it in a position calculated to allow a fluid to be poured into the bottle.

30 With the above and other objects in view, the invention consists in the novel features, details of construction and combination of parts which will hereinafter be more fully set forth, illustrated in the accompanying 35 drawing and pointed out in the appended claim.

Figure 1 is a cross section of the bottle with the collar attached, the lower part being broken away. Fig. 2 is a view similar 40 to Fig. 1 illustrating the position of the extractor for the extraction of the cork from the bottle; Fig. 3 is a section taken on line 3—3 of Fig. 1; Fig. 4 is a section taken on line 4—4 of Fig. 2; Fig. 5 is a vertical section taken through a portion of the bottle, showing the same in a canted position; Fig. 45 6 is a section taken on line 6—6 of Fig. 2.

Referring more particularly to the accompanying drawings, in which like characters of reference refer to corresponding parts in the several views, 5 designates the bottle comprising a body portion 6 and a neck portion 7. The neck portion 7 of the bottle is externally threaded as indicated 50 by the character 8 for a purpose which will

be hereinafter more fully described. Mounted upon the neck portion 7 of the bottle and permanently connected therewith through the medium of the tubular member 9 is a head 10, said head being of hollow tubular 60 formation and having a closed upper end 11. The formation of this head, that is to say, by being of a hollow tubular formation, provides the same with a valve or 65 guard chamber 12, in which is arranged a guard or valve 13. This guard or valve 13 is constructed of an elastic material and is in the form of a nipple, and is formed on the inner end thereof with an annular flange 14 and at its opposite end with a contracted 70 discharge mouth 15. By reason of the fact that this guard or valve member 13 is formed of elastic material, the same may be stretched over and in embracing relation with the neck portion 7 of the bottle 75 disposing the flange portion 14 thereof upon the shoulder 16 of the bottle. A locking member for the guard in the form of a collar 17 is provided and formed with a centrally located internally threaded opening 18 for threadedly engaging with the externally threaded portion 8 of the neck in order to permit the collar to be applied to the bottle, and the same is secured upon the neck until the same reposes upon the 80 shoulder 16 and clamping the flange 14 of the guard between the opposed surfaces of the collar and shoulder respectively, and it will be apparent after the collar has been positioned in the manner described will 85 permanently secure the guard on the bottle and prevent the removal thereof from the bottle. Fastened to the inner contour of the flange 19 is a locking spring secured at one end in the recess 20 through the medium 90 of a fastener 21 and the free end 22 of the spring is adapted to abut with a shoulder 23 should any attempt be made to unscrew the collar from the bottle, thereby preventing 95 its removal. 100

The closed end 11 of the head 10 is provided with a series of discharge openings 24 to permit the fluid from the bottle to be discharged therefrom when the same is tilted. Loosely mounted for vertical sliding movement in the central portion of the closed end 11 is a cork extractor 25 which may be in the form of wire or the like material and has its spiral end 26 engaged with the cork 27 when the cork is positioned 110

within the bottle neck 7, and it will be seen when the cork is in such position the liquid will in no way contact with the guard or valve member 13.

In briefly describing the operation of the invention it is to be stated when it is found desirable to empty the bottle the cork 27 is extracted from the neck 7 and through the guard member 13, the bottle is then tilted and the liquid flows through the guard member and passes out of the bottle through the openings 24. After the bottle has been freed of its contents the same can not be refilled, for the reason that the guard 13 is preferably formed of thin rubber or the like material, whereby the weight of the same will tilt the contracted end 15 of the guard over and upon the shoulder 16 of the bottle. Furthermore, the fact that this guard is preferably formed of thin rubber, will cause the walls forming the contracted end 15 of the guard, due to the moistening of the same by the passage of the liquid therethrough, to cleave or stick together, whereby any attempt to refill the bottle will be prevented.

From the foregoing description, taken in

connection with the accompanying drawings, the advantages of construction and of the method of operation will be readily apparent to those skilled in the art to which the invention relates, and while I have described the principles of operation of the invention together with the device which I now consider to be the best embodiment thereof, I desire to have it understood that the device shown is merely illustrative and that such advantages may be made when desired as are within the scope of the claim appended thereto.

I claim:

A non-refillable bottle embodying a body having a neck, a head fastened on said body, a guard, and an extractor operating axially through said head for extracting a cork from the bottle neck and through said guard.

In testimony whereof I affix my signature in presence of two witnesses.

JAMES GREEN.
